JOHN L. CREVELING, OF NEW YORK, N. Y., ASSIGNOR TO SAFETY CAR HEATING AND LIGHTING COMPANY, A CORPORATION OF NEW JERSEY.

REVERSIBLE BRUSH-HOLDER FOR DYNAMO-ELECTRIC MACHINES.

1,164,261.

Specification of Letters Patent. Patented Dec. 14, 1915.

Application filed October 20, 1911. Serial No. 655,660.

To all whom it may concern:

Be it known that I, JOHN L. CREVELING, a resident of New York, in the county and State of New York, have invented certain 5 new and useful Improvements in Reversible Brush-Holders for Dynamo-Electric Machines, as set forth in the annexed specification and drawings, forming a part thereof.

My invention pertains to that class of 10 dynamos or generators provided with an armature and commutator and has for its particular object to provide a generator which will deliver current of uniform polarity regardless of direction of rotation of 15 the armature.

In the drawing Figure 1 is a partial section and elevation of one type of dynamo comprehending my invention. Fig. 2 is a section of the dynamo shown in Fig. 1 taken 20 on the line A—B as viewed from the right. Fig. 3 is a section of the dynamo shown in Fig. 1 taken on the line C—D as viewed from the right. Fig. 4 is a section of the dynamo shown in Fig. 1 taken on the line 25 E—F as viewed from the right.

In the drawing, 1 represents the armature of my improved dynamo provided with the commutator 2 and supported as by the shaft 3 carried in suitable journals, one of which 30 is indicated at 4.

5 is an end or head casing carrying the journal 4 and provided with a flanged portion 6 secured to the shell or frame of the dynamo 7 as by the screws 8.

35 9 is an annular hollow magnet which may be cast integral with the head 5 if desired and provided with the magnet winding 10 which may be connected across the brushes as diagrammatically indicated in Fig. 1.

40 The casting 5 is also provided with an extending sleeve 11 provided with a recessed or track portion 12 upon which run the sheaves or rollers 13 carried by the arms 14 which support the connecting members 15 which

45 carry the square rods or members 16 free to slide or move longitudinally therein and which carry at one extremity the shoes of magnetic material 17 and at the other extremity, properly insulated therefrom, the

50 brush holders 18. The springs 19 tend to normally move the members 16, 17 and 18 in a right-hand direction and into the position shown in Fig. 1. The brush holders 18 carry the brushes 20 pressed upon the com-

55 mutator 2 as by any suitable spring mecha-

nism, as shown. The brush holders 18 are connected with the conducting members 21 to which the brushes may be better connected electrically as by means of pig-tails or yielding connections 22 and screws 23 if 60 desired.

24 is a conducting ring adapted to make contact with the conducting members 21 when the brush holders 18 and the members 16 and 17 are moved in a left-hand direction, as when the magnet 10 attracts its 65 shoes 17.

25 is a binding post constituting one of the terminals of the machine. This post is insulated from the frame of the generator 70 and in electrical communication with the ring 24 in such manner as to connect the same with an external circuit.

The drawing shows a four pole machine and as Fig. 1 shows only brushes on the 75 same diameter, they are, of course, of like polarity and, therefore, are both connected with the ring 24 when the shoes 17 are attracted. The brushes of opposite polarity are connected with the conductors 26 simi-

80 lar to 21 and provided with contact members 27 similar to those shown at 21. The position of these conductors is on the under side of the members 15 in such manner that when the respective shoes are attracted by 85

the magnet 10, the contact members 27 make contact with the ring 28 as shown plainly in Figs. 2, 3 and 4, and said ring is connected to the external circuit in the same manner as the ring 24 through another 90

binding-post similar to 25, constituting the other terminal of the machine, as shown in dotted lines in Fig. 3. The several means for rotatably and slidably carrying the brush holders and their corresponding 95

brushes are placed upon the sleeve 11 with the sheaves or rollers 13 located in the track 12 and then united in pairs, as shown, by any suitable connecting members as, for example, the conducting springs 29 engaging 100

the hooks 30. Therefore, when the brushes are in place the entire brush carrying mechanism tends to revolve with the commutator owing to the friction between the brushes and the commutator. At any time the 105 brush carrying mechanism may be taken out by simply releasing the springs 29, the apertures 31 being made in the field frame or shell for this purpose.

32 is a spacing disk provided with s 113

36 engaging the connecting members 15 in such manner as to insure the same remaining in proper relative relation. Said disk 32 is free to revolve upon the hub 33 within 5 the limits prescribed by the stop 34 and the coöperating slot 35. In a four pole machine, as shown in the drawings, the slot 35 allows substantially 90 degrees revolution of the brush carrying mechanism and, therefore, 10 if the armature be revolved in one direction the brushes will travel with the commutator until at the ends of the proper axes of commutation and then, if the generator be revolved in the opposite direction, the 15 brushes will revolve until in the position at the opposite axes of commutation as may be determined by properly arranging the slot 35 and stop 34.

The operation of my improved dynamo is 20 substantially as follows:

If the brush carrying mechanism for all the brushes has sheaves or rollers 13 placed in the track 12 and they are united as by the springs 29, as shown in Figs. 1 and 2, and 25 if said brush carrying mechanism be placed with its extending portion within the slots 36 of the spacing disk 32, as shown in Figs. 1 and 4, and the brushes be placed in proper position as indicated in Fig. 1, then, if the 30 dynamo has its armature revolved in one direction or the other, the entire brush carrying mechanism will revolve with the commutator until arrested by the stop 34 coöperating with the end of slots 35 which will arrest 35 the brushes in their proper positions upon the axes of commutation. If the generator speed then be increased until the voltage be appreciable the magnet 10 in shunt across the brushes will be energized and attract 40 the shoes 17 against the action of springs 19 and firmly hold the shoes in place in such manner as to firmly support the brush holders 18 and prevent any chattering or vibration thereof. As the magnet 10 attracts 45 the shoes 17 it will also connect the brush holders and brushes with the rings 24 and 28, the two diametrically opposite brushes shown in Fig. 1 being connected with the ring 24 and the two brushes at 50 right angles thereto of opposite polarity being connected as by the conductors 27 shown in Figs. 2, 3 and 4 with the rings 28, the rings 24 and 28 being connected with the external circuits as by the binding-posts 25, 55 one of which is shown in Fig. 1 and both of which are shown in dotted lines in Fig. 3. If now the generator stop and the electro-motive force fall to zero, the electromagnet 10 will release the shoes 17 and the brush 60 holders will be pressed into the positions shown in Fig. 1 by the springs 19. If the generator then be started in an opposite direction the brushes 20 will cause the entire brush carrying mechanism to revolve 65 through an arc of 90 degrees or until arrested

by the stop 34 and then the electromagnet 10 will become excited and attract the shoes 17 and establish the external circuit connection and firmly support the brushes as outlined above. It will be obvious that shifting of 70 the brushes from one axis of commutation to the other will cause the generator current to be of uniform polarity regardless of direction of rotation of the armature.

From the foregoing it will be plain that I 75 have produced a dynamo, or generator, of simple construction in which the brushes are free to revolve into proper positions to preserve uniform direction of current upon reversals of rotation of the armature and in 80 which the brushes are firmly supported when the generator is operative and the ill effects of chattering and vibration avoided. It will further be obvious that the brush carrying mechanism may readily be removed 85 from the generator for inspection or repairs and that this may be done without necessitating the disconnecting of flexible or yielding connections or pig-tails connecting the brush carrying mechanism with some fixed 90 member of the generator.

I make no claim herein to the broad idea of magnetic means for holding the brushes at the point of arrest, nor to the idea of means of holding the brushes under control 95 by the current generated by the machine, nor to a fixed stop in the proper combination for limiting the movement of the brush-holders, as these various features of invention are made the subject of my application 100 filed August 7, 1911, Serial No. 642,582. Nor do I make claim herein to magnetic means broadly for restraining the brush-holders, nor anti-frictional means broadly 105 for supporting the brush-carriers, as such features of my invention are made the subject of my said application Serial No. 644,983. Nor do I make claim herein to the broad idea of means of supporting the 110 brushes upon the commutator, in combination with means for restraining the movement of the brushes, nor the broad idea of means of securing the brushes together about the commutator, as all such means and features of my invention are, in the proper 115 combinations, made the subject of my application, Serial No. 651,022, filed September 25, 1911.

I do not wish in any way to limit myself to the exact details of construction or to the exact mode of operation set forth in this specification to illustrate one type of dynamo embodying my invention, for it will be obvious that wide departure may be made in the way of details without departing from the spirit and scope of my invention which is as set forth in the following claims:

1. A dynamo electric machine having, in combination, a frame providing a journal-bearing, an armature shaft journaled in said 130

- bearing, and a commutator carried by said shaft; a reversible brush mechanism comprising a plurality of carrying devices arranged about and bearing upon the said journal; a brush-holder mounted in each of said carrying devices by means permitting movement of the same relatively thereto; means for connecting the carrying devices together so that they may all move in unison; means for limiting such unitary movement; and independent means for holding the brushes at the limit of such movement whereby vibration and chattering of said brushes is avoided.
2. In a dynamo electric machine, a brush-carrying mechanism comprising a plurality of parts connected together and mounted so as to move with the armature shaft in either direction of rotation; a plurality of brush-holders mounted upon said brush-carrying mechanism by means enabling the same to slide relatively thereto; means for limiting the rotation of the carrying mechanism to correspond with the different diametrical axes of current commutation; brushes mounted in the brush-holders; circuits and circuit connections between the several brushes and the terminals of the machine whereby the current is maintained in a constant direction for reversals of rotation of the commutator; and means acting upon said brush-holders for securing the same from movement at the limit of rotation of the carrying mechanism.
3. In a dynamo electric machine, a brush-carrying mechanism comprising a plurality of parts connected together and mounted so as to move with the armature shaft in either direction of rotation; a plurality of brush-holders mounted upon said brush-carrying mechanism by means enabling the same to slide relatively thereto; means for limiting the rotation of the carrying mechanism to correspond with the different diametrical axes of current commutation; brushes mounted in the brush-holders; circuits and circuit connections between the several brushes and the terminals of the machine whereby the current is maintained in a constant direction for reversals of rotation of the commutator; mechanical means for maintaining the brush-holders normally in a predetermined position relatively to the carrying mechanism; and means for shifting said brush-holders from said predetermined position and to hold the same against movement at the limit of rotation of the brush-carrying mechanism.
4. In a dynamo electric machine a reversible brush holder embracing rotatable brush-carrying means journaled to rotate with the armature shaft, comprising a plurality of slideable brush-holding devices provided with yielding means for holding the same in a definite position laterally; electro-
- magnetic means for holding them in reverse position when energized; means for limiting the rotation of the carrying means in either direction to correspond to the different diametrical axes of current commutation; together with circuits and circuit connections between the several brushes and the terminals of the machine whereby the current is always maintained constant in direction for reversals of rotation of the commutator.
5. In a dynamo electric machine a reversible brush-holder embracing rotatable brush-carrying means journaled to rotate with the armature shaft, comprising a plurality of independently slideable brush-holding devices provided with yielding means for holding the same in a definite position laterally; electromagnetic means for holding them in reverse position when energized; means for limiting the rotation of the carrying means in either direction to correspond to the different diametrical axes of current commutation; together with circuits and circuit connections between the several brushes and the terminals of the machine whereby the current is always maintained constant in direction for reversals of rotation of the commutator.
6. In a dynamo electric machine a reversible brush-holder embracing rotatable brush-carrying means journaled to rotate with the armature shaft, comprising a plurality of independently slideable brush-holding devices provided with mechanical means for holding the same in a normal position relatively to the commutator; electromagnetic means for holding them in reverse position when energized; means for limiting the rotation of the carrying means in either direction to correspond to the different diametrical axes of current commutation; together with circuits and circuit connections between the several brushes and the terminals of the machine whereby the current is always maintained constant in direction for reversals of rotation of the commutator.
7. In a dynamo electric machine; a brush-holder; means for mounting the same so as to be movable with respect to the commutator of said machine; means for producing movement of said brush-holder; and means operated by the brush-holder when the same is moved, to make connection with an outside circuit.
8. In a dynamo electric machine having a commutator; the combination of a brush-holder and brush carried thereby; means for mounting the brush-holder so as to be movable; means for producing such movement; a conductor carried by the brush-holder in electrical relation with the brushes carried thereby; and a fixed conductor adapted to be connected to an outside circuit mounted in such position with respect to the conductor carried by the brush-holder, that when the

brush-holder is moved the conductor carried thereby will be forced into contact with the fixed conductor.

9. In a dynamo electric machine; the combination of a commutator and a brush-holder; means for mounting said brush-holder movable circumferentially of the commutator; said brush-holder being so connected with said mounting means as to be movable axially, both with respect to the mounting means and the commutator; and means for preventing further movement of the brush-holder when the axial movement thereof has taken place.
10. 10. In a dynamo electric machine; the combination of a commutator; a brush-holder associated therewith; means for movably mounting said brush-holder to enable the same to change its position when the rotation of the commutator reverses and means for holding the brush-holder against further movement after the reversal of the commutator, and automatically connecting the armature of the machine with an outside circuit.

11. In a dynamo electric machine; the combination of an armature and a commutator; a brush-holder associated with the commutator and carrying one or more brushes; means for mounting the same to enable the brush-holder to change its position when the rotation of the commutator reverses; and means for producing further movement of the brush-holder after the commutator reverses, without changing the position of the brush-holder with respect to the axes of rotation, to secure the mounting means against further movement, and at the same time automatically connect the brushes to an outside circuit.

12. In a dynamo electric machine, the combination with a commutator; of a brush-holder associated therewith and carrying a plurality of brushes; means for mounting the brush-holder enabling it to change its position when the rotation of the commutator is reversed; means for maintaining a fixed angular relation of the brushes relatively to the commutator, irrespective of the movement of the latter; and means for holding the brushes from movement at the limit of movement of the brush-holder upon reversals.

13. In a dynamo electric machine the combination of an armature and a commutator; a brush-holder associated with the commutator and carrying a plurality of brushes; means for spacing the brushes apart so as to hold them in fixed relation to each other; means for mounting the brush-holder en-

abling it to change its position when the rotation of the commutator reverses; means coöperating with the spacing means for limiting the rotation of the brush-holder relatively to the commutator; and means for holding the brushes stationary at the extreme points of movement of the brush-holder.

14. In a dynamo electric machine the combination of a commutator; a brush-holder and brush associated therewith; means for movably mounting the brush-holder enabling it to change its position when the rotation of the commutator reverses; a magnet and a shunt connection to the brush for holding the latter at the limit of rotation of the brush-holder, substantially as described.

15. In a dynamo electric machine the combination of a commutator; a brush-holder associated therewith; means for mounting the brush-holder enabling it to move with the commutator; means for limiting such movement; and means acting directly upon the brush-holder for moving the same in a right-line direction whereby to position the same relatively to the commutator and hold it from further movement at its limit of rotation.

16. In a dynamo electric machine the combination of a commutator; a brush-holder associated therewith; means for mounting the brush-holder enabling it to move with the commutator; means for limiting such movement; and means acting directly upon the brush-holder for moving the same in a right-line direction whereby to position the same relatively to the commutator and hold it from further movement at its limit of rotation; and means for restoring said brush-holder to its normal position after the influence of the last-named means has ceased.

17. The combination with a commutator and brushes in operative relation thereto; of brush-carrying means allowing some motion of the brushes with the commutator; means for arresting said motion with the parts in position for connecting the brushes with the circuit terminals so said brushes may be connected with opposite branches of said circuit upon reversals in direction of the commutator; and means including an electromagnet excited by current collected from said commutator for magnetically holding the brushes in fixed operative position and simultaneously establishing said connection.

JOHN L. CREVELING.
